UNITED STATES PATENT OFFICE.

GEORGE WATSON McALLISTER, OF SAN FRANCISCO, CALIFORNIA.

ROTARY DRILL.

1,113,132.

Specification of Letters Patent.

Patented Oct. 6, 1914.

Application filed March 8, 1911. Serial No. 613,064.

To all whom it may concern:

Be it known that I, GEORGE WATSON McALLISTER, a citizen of the United States, residing at San Francisco, in the county of San Francisco and State of California, have invented a new and useful Rotary Drill, of which the following is a specification in such full and clear terms as will enable those skilled in the art to construct and use the

same.

This invention relates to a rotary well drill, and its object is to produce a drill which can be used for prospecting oil fields to any desired depth with the greatest possible speed. It will be noticed by those skilled in the art, that it is frequently necessary to put down prospecting holes to ascertain the strata of given locations in order that it may be determined whether or not a regular size oil well will be profitable.

In the present invention, the apparatus is so designed as to be intended to drill continuously, all of the apparatus being especially designed to keep the drill and drill rods rotating at all times.

Another object of the invention is to produce a driving mechanism which will be capable of rotating the drill rods and bit under such pressures as are demanded there- 20 of without in any way interfering with the feed of the drill rods therethrough.

A further object of the invention is to produce a gripping device which will be capable of being applied to the drill rods as the drilling proceeds, without in any way interfering with the rotation of said rod as a whole.

A further object of the invention is to provide means whereby fresh length of drill 40 rod may be applied to the rod in use without stopping the rotation of the main drill shaft or rod.

A further object of the invention is to produce a drill which will operate with a 45 minimum clearance whereby it is possible to pump cement between the casing and the hole to close off water bearing strata from the oil bearing strata.

It will be understood by those skilled in 50 the art that where the rotary drill is used and where the pulverized rock passes up outside of the drill, it is very difficult to prevent the hole from becoming larger than it should be and it is difficult to keep such a hole from 55 permitting the water to pass down into the oil bearing ground, thus causing consider-

able losses. With this invention the clearance is determined by the size of the crushed steel used and by using a bit having more or less set as the case may be, but in any event 60 it is contemplated that the clearance shall be as small as possible. During the drilling operations, the cement can then be forced into the well between a short piece of casing sunk to the first impervious stratum and the 65 drill rods from any suitable pump capable of pressure up to 150 pounds, and a thin but effective casing thus formed outside the drill rods to seal off otherwise troublesome water strata from the strata below that require 70 protection. When the desired depth has been reached, and a knowledge of the formation obtained, permanent protection of the valuable oil bearing sands may be had by cementing the entire hole by filling it with 75 cement through the center opening as the rods are withdrawn. A further advantage of this apparatus is that it permits the taking of samples through the central opening of the drill rod by lowering a thin steel tube 80 having a suitable valve at the lower end to the topmost core-breaker at which point it can be filled with a sample much less diluted than it would be if sent to the top by an excess of water forced through the down- 85 flow openings. A further advantage of this design is that each of the several parts of the apparatus may be made light enough for mule-back transportation. Continuity of 90 operation is secured by duplicating the motor and transmission parts of the mechanism, so that one-half will be idle most of the time but can be put into operation immediately by suitable clutches when required. This duplication of the power 95 plants is, however, omitted from the drawings since it forms no part of the invention.

Other objects of the invention will appear as the description proceeds.

When the character of the various oil and water bearing strata have been determined and charted, the boring for production of oil can be done with the greatest advantage and with the least waste of drilling funds. When the producing well is put down, suitable 105 precautions for the prevention of the admission of water to the oil bearing strata can then be taken.

In the drawings in which the same numeral of reference is applied to the same 110 portion throughout the several views, Figure 1 is a side elevation partly in section

of the main driving apparatus, the drill grips, the water swivel and the means for adding to the drill rod a fresh length of pipe. Fig. 2 is a plan view of the apparatus 5 illustrated in Fig. 1. Fig. 3 is a broken view of a portion of the driving wheel illustrating the manner of holding the driving shells, Fig. 4 is a plan view of one of the drill rods, Fig. 5 is a vertical sectional view 10 of the water swivel, Fig. 6 is a vertical sectional view of a portion of one of the supporting frames and the supporting cones, Fig. 7 is a plan view of one of the supporting beams, a portion of the supporting cone 15 being broken away therefrom for purposes of illustration, Fig. 8 is a side elevation of one-half of the driving pulley for assembling a fresh length of drill, Fig. 9 is a plan view of said pulley, Fig. 10 is a side elevation 20 of said pulley showing one of the locks for holding the two parts thereof together, Fig. 11 is a longitudinal sectional view of the two driving shells, Fig. 12 is an end view of the two driving shells, and Fig. 13 is a 25 view of the two driving shells looking at the opposite ends from those shown in Fig. 12.

The numeral 1 represents the drill bit to which is secured the coupling 2 and series 30 of drill rods 3. It is intended to use drill rods of a convenient length, which is about 5 feet, fresh drill rods being added at the top as the bore proceeds. At the ground elevation there is a platform 4 having suitable uprights 5 secured thereto for the support of the several parts of the apparatus. At the top of the supports 5 there is a cross-member or girder 6 extending horizontally for the support of the feed screws 7 and 8, 40 said girder also supporting a beam 9 upon which is journaled a revoluble support 10 for temporarily holding the well rods when it is desired to add or take out a length of rod. The beam 9 is provided with ball 45 races for series of balls 11 and 12, the former being near the bottom of the beam while the latter is at the top. These balls support the member 10 revolvably, said member comprising a ring 13 at the bottom 50 thereof and a ring 14 at the top thereof, I beam struts 15 spacing the two rings apart. Each of the rings 13 and 14 is provided with a number of balls 16 which project within said rings for the purpose of catching 55 and holding the two supporting grips 17. The two supporting grips 17 are frustoconical on the outside and they have cylindrical openings therein to grip the well rod. The two members 17 together form a complete circle and are intended to be dropped 60 into place in the support 10 when it is necessary to change or add a fresh length of well rod. It will be noted that the balls 16 are placed in curved seats, said curve 65 enabling the grip to be held tightly by said

balls and thus permitting rotation of the support 10 on the ball sets 11 and 12. Since grips 17 will be rotating with the drill rod when they have been dropped into place in the support 10, some means of removing them therefrom must be provided; this means in a flange 18, which is integral with the top of each half of the grip 17. This enables a flat bar to be inserted below the flanges 18 while the grips are rotating, and, 75 upon lifting the entire set of well rods, the grips may be elevated, and as soon as elevated will free themselves from the well rod. In order to insure the proper holding effect upon the polished surface of the drill rods, each of the grips 17 is provided with a series of inserts 20 of such material as to give the desired amount of friction when pressed against the drill rod.

Secured above the support 5 is a support 21 which extends upwardly and carries a beam 22, the latter having suitable cross-beams for the journals of the feed screws 7 and 8. The feed screws extend vertically, one of them having a bevel gear 24 in mesh 90 with a bevel gear 25 on a shaft 26. The shaft 26 is provided with a crank 27 to rotate the feed screws. In order to insure the equal rotation of each feed screw, each screw is provided with an extension thereof 95 which projects through the beam 9 and which carries a sprocket wheel 28 for a chain belt 29 passing therearound in order to drive each screw equally. The feed screws support a beam 31 substantially like 100 the beam 9 save that as the feed screws rotate the beam 31 travels up or down the feed screws as may be desired. This beam 31 carries a support substantially the same as the support 10, a plate 33 at the bottom thereof being bolted thereto to prevent said support from being dislodged from the beam. This support in turn is provided with similar inwardly projecting balls for 105 the purpose of catching a pair of grips 34 substantially the same in every respect as the grips 17.

At the top of the set of drill rods the water swivel 35 is threaded onto said rods. The water swivel comprises a bail 36 supporting 115 an annulus 37, having projecting ears 38 which pass through eyes in the ends of the bail. The annulus 37 is provided with a ball race on its upper side in which there are balls 39, said balls forming the support for 120 the flanged drill rod head 40. This head 40 is threaded precisely the same as the couplings, and since the openings in the drill rods are open to the threads, it is necessary to provide means whereby the water may be prevented from escaping at the junction of the head 40 and the outer sleeve of the drill rod to which the head is secured. This means comprises an apron 41 which fits the 125 outside of the drill rod snugly and which is 130

5 curved at its lower end to permit the easy insertion of the fresh drill rod therein. The apron 41 has an additional object in that it is used for the purpose of releasing the water swivel from the drill rod when the fresh length of drill rod has been bored to a proper depth.

10 In order to insure absolutely smooth and perfect working of the revoluble parts of the water swivel with respect to the fixed parts thereof, a ring 42 is secured to the depending portion of the head 40 and it has a ball race with balls 43 therein, this flange also preventing dislodging of the head from 15 the ring 37 during the several operations of changing from one drill length to another.

The head 40 is provided with an upwardly projecting threaded nipple 44 having an opening therethrough which corresponds to 20 a central opening in the drill rods, and surrounding this opening there are four smaller openings which permit the water to flow to the outer openings through the drill rods, said openings terminating in a circular 25 groove 45 on the inside of the head. This circular groove 45 matches a similar one on each drill rod and thus insures against closing of the longitudinal openings should the 30 position of the head with respect to the drill rod be changed a few degrees. That is, it is well understood by those skilled in the art, that it is very difficult to screw a coupling or member such as the head 40 to exactly the same place each time, so that there 35 might be a slight slip. Supported upon the head 40 and surrounding the nipple 44 at a portion thereof which is not threaded is a fixed water feed plate 47, said feed plate being suitably packed at 48 to prevent the 40 escape of the water therefrom when forced thereinto through the opening 49. A suitable pipe 50 is threaded into the plate 47 for the purpose of passing water thereinto and for holding said plate from rotating.

45 Screwed upon upper end of the nipple 44 is a member 51 which rotates with the head 40 and which holds the plate 47 down into contact with the top of said head. This member 51 has an opening therethrough 50 large enough at its upper end to receive the water discharge sleeve 53, suitable packing being placed at 54 to prevent the discharge of water on the outside of said sleeve 53.

The sleeve 53 is secured in place by means 55 of the ring 55 which is bolted to the top of the sleeve 51. The sleeve 53 has a pipe 56 connected thereto for the discharge of water and cut rock, said pipe also holding the sleeve 53 from rotating. It will be understood 60 by those skilled in the art, that the water swivel is connected with a cable which passes through the head of the drill rig in a manner well known, but which is not shown here since not a part of this invention.

The entire length of drill rods is driven from a large bevel wheel 60. This wheel is supported in turn upon uprights 61 of which there may be any desired number, and it is preferably supported upon some form 70 of anti-friction bearing since the power required to drive such a drill as this is considerable and none of it should be wasted. This bevel wheel carries bearings 62 above and below, said bearings supporting rolls 63, 75 each set of rolls being placed at right angles to the other set. The shafts of these rolls project through the bearings 62 and the two shafts of each set are connected by means of links 64, said links extending substantially straight across from one shaft to the other and being pivoted together at 65, said pivot supporting weight 66 for the purpose of drawing the two rolls together, thus enabling the driving grips 67 to be very 80 tightly held together. The weight 66 is assisted in its object by means of a rod 66' which is connected to the links 64 and which passes through the web of the large bevel wheel. This rod has a heavy spring 66' 85 thereon and a nut 66'' bears upon a washer below the spring. This enables the pressure of the rolls to be regulated to a certain extent and secures them flexibly together.

Because of the small diameter of the well rods 8, and because of the fact that they are rotated by the rolls 63 with a line contact, it is necessary to increase the driving radius and the coefficient of friction between the rods and the drive wheel. 90 This is accomplished by means of grips 67, which are thick enough to increase the driving radius and to give a better grip upon the well rods as they contain high coefficient inserts inside and outside. The necessity of placing two sets of driving rolls at right angles to each other is because of the fact that the grips must be inserted either upon raising the well rods or upon lowering them when they are rapidly rotating. This 100 might bring two of the grips 67 between the driving rolls in such a manner as to be liable to permit them to be so caught as not to grip the drill rod. But this is entirely avoided with the two sets of rolls at right 105 angles to each other since should one set of rolls be so placed upon the grips the other set would be sure to be placed in such a manner as to adequately hold the drill rod.

Driving wheel 60 is driven from the bevel wheel 70 on a shaft 71, journaled in bearings 72, said shaft receiving power from any suitable source, as, for example, a pulley 73. The intention being to operate the drill rod continuously, it becomes necessary to provide means whereby fresh lengths of rod can be added from time to time without in any way interfering with the drilling operations. It will of course be necessary to drive the entire set of rods 125 130

in such manner as to cause each of them to tighten in the threaded sleeve secured thereto. It will thus be possible to remove any rod from the set of rods by simply exerting such pressure against the same as to cause it to be retarded or stopped in its rotation, such pressure being applied thereto as will be necessary to loosen it in the coupling thereon. In a similar manner it is possible to add new rods to the top by increasing the rotation of the fresh rod above that of the drill rod in use. Therefore, when it is desired to add a new section to the rods in use, the lower grips 17 are dropped into place against the drill rod. The beam 31 is then raised to the top of the screws supporting the same, the water swivel having been first removed from the top of the well rod by retarding it by friction against the depending apron 41. When the beam 31 is in a raised position free from all of the rods, the grips therein are raised so as to be free from a new section of rod which is placed therethrough. The water swivel is then connected to the top of the fresh section of rod and the pulley shown at 75 is secured on said fresh section of rod near the lower end thereof. This pulley 75 is divided into two portions, as illustrated in Figs. 11 and 12, and it is grooved around its periphery to receive a rope belt 76. Since this pulley is only intended for the purpose of placing the fresh section of rod on the section in use, the power required to be transmitted by it to the fresh section of rod is only that required to screw the fresh section of rod on the section in use. It is therefore necessary to provide means whereby it may be pressed tightly enough against the fresh section of rod to screw it into place. A temporary lock 76' is provided to hold the two parts of the pulley together when it is being placed upon the fresh section of rod. This lock 76' has depending ears 77 which pass into openings in each of the halves of the pulley thus holding the two halves together. Connected with the center of the lock 76 is a rod 78 which is long enough to extend entirely through the pulley and project from the bottom thereof as much as the points 77 project below the general body of the lock 76. Each half of the pulley has a groove cut therein, as illustrated at 79, the object being to provide a shoulder against which the spring 80 may be tightened, this spring being of such strength as may be necessary to hold the two parts of the pulley against the fresh drill section to drive the same into place. The pulley having been placed into position upon the fresh section, a belt 76 is passed thereover, the guide arm 81 holding the rod in place. This guide comprises two arms having rollers 82 at their movable ends and adjustable vertically upon posts 82',

collars 83 holding said arms in any desired position. The purpose of the arms 81 is to hold the fresh drill section at a fixed distance away from pulleys 84 over which the belt 76 passes. These arms are secured together at their free ends by means of a block 81' and bolt 81'' which permit a certain lateral adjustment thereof. The reason for this lies in the fact that the pulley 75 is driven by said belt 76 upon the tightening thereof, and it is necessary to hold said drill section at a fixed distance from said pulley 84 to drive it and to secure it to the rods in use.

The pulleys 84 are supported on a horizontal shaft 85 suitably journaled in the framework of the apparatus. These two pulleys change the direction of the movement of the belt 76 to enable it to be driven from the main drive shaft 71. The main drive shaft is provided with a pulley 87 below which the belt 76 passes, and loosely mounted upon the shaft 71 is a lever 88, said lever carrying a small pulley 89 which is used as a belt tightener to drive the pulley 75 when necessary. The belt 76 is crossed between the pulley 87 and the pulleys 84 in order to give the proper direction of rotation to the fresh length of drill rod. The lever 88 is lifted up and pressed against the belt 76 to tighten it sufficiently to rotate the fresh drill section at the desired speed. Since it becomes necessary to rotate the fresh drill section faster than the rotation of the main drill rods to connect it thereto, the proportions of the gears 60 and 70, and of the pulleys 75 and 87 must be such that it is possible to rotate the pulley 75 slightly faster than the rotation of the gear 60.

The grip inserts 67 are substantially half-cylindrical shells having their ends so formed as to readily adapt themselves to the necessary crowding into and out of the drive rolls 63. The lower ends of these grips form together a frustum of a cone, as shown at 90, which tapered ends fit within the oppositely-tapered end of the next adjacent section. The object of this is to make easier the insertion and removal of fresh grips, as may be necessary.

Since this drilling apparatus is intended to be operated continuously when the hole is started and until the rods are withdrawn therefrom, it becomes necessary to use some form of a drill rod and bit which is especially adapted for the purposes to be carried out by the apparatus. Such a drill rod is shown in Figs. 16 and 19, the former of which is a plan thereof, and the latter a side elevation of one end of one of said drill rods, each end of each rod being identical. The rod comprises an inner member 90, which is formed with an opening therethrough, as shown in Fig. 16, and with water supply channels 91 at the sides thereof,

this particular form being chosen for convenience in manufacture. This inner member 90 is threaded at each end as illustrated in Fig. 19, and a sleeve 92 is shrunk thereon to complete the channels 91 and to give additional strength to the rod. Inasmuch as the precise position of each coupling with respect to the drill rod to which it is secured can not be exactly predicted when the coupling and rod are put together as is contemplated herein, it becomes necessary to groove the inner member 90, as shown at 93, so that when the coupling is placed thereon, there will be a continuous channel from one rod to another through each coupling.

The operation of the apparatus is substantially as follows: Assuming a hole to be started and the apparatus ready to run, 20 a number of connected drill rods are placed in position between the rolls 63. The grip inserts 67 are then placed upon the rods and are forced between the rolls 63, the pressure upon said grips being great enough to do 25 the necessary driving. The water swivel is then connected at the upper end of the set of rods, and the machine is ready to start, the grips 34 being placed in position against the well rods. Since at this time the drilling 30 is just starting, the beam 31 will be near the top of the feed screws 7 and 8. The machine is then started and the drilling proceeds, the persons in charge feeding the beam 31 down as becomes necessary. As the drilling 35 proceeds and the beams 31 descends, the grips 17 are placed within their support, although held off from said support to prevent them from catching the drill rods. The drilling then continues until the beam 31 gets as 40 close to the grip 17 as is desirable. When this has happened, the grips 17 are released and are dropped against the drill rods. They will then engage and hold said drill rods from any downward movement, as soon 45 as any weight of the rod comes upon them. This is accomplished by slightly lowering the beam 31, while at the same time the grips 34 are prevented from being carried down thereby. As soon as the beam 31 has lowered slightly, the grips 34 are released from 50 the drill rod, and may easily be removed therefrom, the water swivel having been first removed from the drill rod by stopping the same by placing some form of a brake 55 against the apron 41. After the two grips 34 are removed from their support, the beam 31 may be raised to the top of its feed screws, whereupon a fresh length of drill rod is secured to the water swivel. 60 This drill rod is then passed through the support for the grips 34, and the water swivel is lowered to a position close to said grips, the latter for the time being, being held away from the fresh drill rod. The 65 pulley 75 is then secured to said fresh length

of drill rod, and the two arms 81 are secured against the same to prevent it from being pulled out of line. It will be understood, of course, that during all of this time the main set of drill rods is being continuously rotated by the rolls 63. When the pulley 75 has been placed in position, and when the arm 81 is placed against the fresh drill rod, all that is necessary is to lower the drill rod against the drills then in use. The belt tightener 88 is at the same time pressed against the belt 76 to cause the fresh length of drill rod to be rotated faster than the drill rods in use. The fresh length of drill rod is then brought into contact with the drill rod in use and it is quickly tightened into position by means of the belt 76. As soon as it is tightened sufficiently, the springs 80 may be knocked off the pulley 75 and the locks 76 may then be driven up, whereupon the pulley will fall upon a suitable platform and will quickly cease rotating. It may then be removed from the drill shaft, and the grips 34 will then be dropped into position against the fresh length of drill rod. The grips 17 may then be removed by lifting the beam 31 slightly, while the grips 17 are at the same time raised slightly. As soon as grips 17 are loosened, they may be blocked up out of contact with their support, or 95 may be removed therefrom if desired. The drilling is then ready to proceed again until the fresh length of drill rod is used up, whereupon the operations are repeated. The advantage of this form of apparatus lies in 100 the fact that the drills may form a hole with the smallest possible clearance, since none of the crushed material passes outside the drill rod, all of it being discharged through the central opening in the drills. A further 105 advantage lies in the fact that the drills may be kept running at all times, thus doing away with the liability to breakage due to the drills becoming "set" in the hole, when the drilling operations are discontinued 110 for a short period, as in the changing of the rods. A further advantage of this apparatus lies in the fact that it becomes a very simple matter to determine absolutely what stratum is being penetrated at any given 115 moment, since all that is necessary to determine exactly the stratum being penetrated is to stop the downward progress of the drill and to continue flushing the hole until clear water is passed out, whereupon it can be with certainty determined what the stratum is. The difficulty of doing this where the crushed rock and water passes from the hole outside of the drill rods will be obvious when it is considered that all of said material is rubbed and abraded against the entire length of the hole in which occurs all kinds of strata.

While screws have been shown for the purpose of feeding the drill rods down- 130

wardly, it will be understood by those skilled in the art that any form of feeding mechanism may be used, as, for example, the hydraulic feed might equally well be used in the place of the feed shown.

Having thus described my invention what I claim as new and desire to secure by Letters Patent of the United States is as follows:

- 10 1. In a mechanism for continuously rotating a drill rod and comprising a driven wheel, two pairs of grooved rollers, the axes of one pair of rollers being at 90° to the axes of the other pair, adapted to contact with the part to be driven, and links connecting the journals of said grooved rollers whereby they may be drawn together to grip said driven rod, substantially as described.
- 20 2. In an apparatus for continuous drilling, a support for a drill, said support comprising a beam carrying anti-friction bearings, a revolute member supported upon said bearings, and frusto-conical shells adapted to contact with the drill rod to prevent its longitudinal movement and to permit its rotation with said revolute support, substantially as described.
- 30 3. In an apparatus for operating a drill rod continuously a driven wheel, grooved rollers carried thereby, a drill extending between said grooved rollers, and semi-cylindrical shells adapted to be placed upon said drill rod and to contact with said rollers to rotate said rod, substantially as described.
- 40 4. In an apparatus for continuously rotating a drill rod means to rotate said drill rod continuously, means to support said drill rod to prevent its downward movement, and means whereby a fresh length of drill rod may be screwed into place at the top of the rods being rotated without stopping the rotation of said rods, substantially as described.
- 50 5. In an apparatus for continuously operating drill rods a set of drill rods, a driven wheel, rollers carried thereby to rotate said rods, a support to prevent the downward movement of said drill rods, a removable pulley adapted to be connected with a fresh section of drill rod, means to hold said fresh section of drill rod in a position over the rods being rotated, and a belt passing around said pulley to rotate said fresh section of rod more rapidly than the rods then in use, substantially as described.
- 60 6. In an apparatus for the continuous rotation of drill rods a set of drill rods, a driven wheel through the center of which said set of drill rods passes, grooved rollers carried by said wheel to rotate said set of

rods, a support for said drill rods, means to feed said drill rods downwardly as desired, and a water swivel having a feed pipe and discharge pipe connected therewith, substantially as described.

7. In an apparatus for continuously rotating drill rods a set of drill rods, a driven wheel through which said drill rods pass, grooved rollers carried by said wheel for rotating said drill rods, a support to prevent the downward movement of said drill rods, a pulley adapted to be secured to a fresh length of drill rod, a movable arm to hold said fresh length of drill rod in a fixed position, a belt passing over said pulley and passing over a pulley of such diameter on the main drive shaft as to permit the more rapid rotation of the fresh length of drill rod than the rotation of the sections then in use, and a water swivel to be secured to the fresh drill section, substantially as described.

8. In an apparatus for continuous drilling a set of drill rods, means to rotate them continuously, a fixed support adapted to hold said drill rods from longitudinal movement when a fresh length of drill rod is to be added, a second and movable support adapted to feed said drill rods downwardly as required, and a water swivel connected to the upper end of the drill rods, substantially as described.

9. In an apparatus for the continuous rotation of drill rods a set of drill rods, means to continuously revolve said drill rods, a revolute support to prevent the downward movement of said drill rods, a second vertically movable revolute support to feed said drill rods downwardly as required, a support for holding a series of continuously rotated drill rods, said support comprising a frame revolute on anti-friction bearings, and frusto-conical shells adapted to contact with said drill rods and with said support to prevent the downward movement of said drill rods, substantially as described.

10. In a support for continuously rotated drill rods, a beam, a frame supported upon anti-friction bearings upon said beam and revolute thereon, balls projecting within said frame, and frusto-conical shells adapted to contact with a drill rod, and with said inwardly projecting balls carried by said frame, substantially as described.

In testimony whereof I have hereunto set my hand this 2nd day of March A. D. 1911, in the presence of the two subscribed witnesses.

GEORGE WATSON McALLISTER.
